UNITED STATES PATENT OFFICE.

HARRY E. THOMPSON, OF THREE RIVERS, MICHIGAN, ASSIGNOR TO SHEFFIELD CAR COMPANY, OF THREE RIVERS, MICHIGAN.

WATER-COLUMN.

1,286,448.

Specification of Letters Patent.

Patented Dec. 3, 1918.

Application filed July 29, 1918. Serial No. 247,115.

To all whom it may concern:

Be it known that I, HARRY E. THOMPSON, a citizen of the United States, residing at Three Rivers, in the county of St. Joseph 5 and State of Michigan, have invented certain new and useful Improvements in Water-Columns, of which the following is a specification.

This invention relates to improvements 10 in water columns.

The main objects of this invention are to provide an improved water column having a vertical rotatable standpipe or upright which is supported so as to be easily rotatable 15 and the wear upon the parts and packing minimized.

Further objects, and objects relating to structural details, will definitely appear from the detail description to follow.

20 I accomplish the objects of my invention by the devices and means described in the following specification. The invention is clearly defined and pointed out in the claims.

A structure which is a preferred embodiment 25 of my invention is clearly illustrated in the accompanying drawing forming a part of this specification, in which:

Figure I is a detail vertical central section of a structure embodying the features of 30 my invention.

Fig. II is a horizontal section on a line corresponding to line 2—2 of Fig. I, the bearing of the centering ball being shown in full lines.

35 Referring to the drawing, similar reference characters refer to similar parts in both views.

Referring to the drawing, I have not illustrated full details of the valve mechanism 40 nor of the upper part or delivery mechanism of the standpipe as these features form no part of my present invention. Among others I have in practice embodied my improvements in structures having the delivery mechanism shown in my application for Letters Patent, Serial No. 236,814, filed May 27, 1918.

1 indicates the conduit connecting the valve casing 2 with the water main or source of 50 water supply. The valve is indicated gen-

erally by the numeral 3. The valve casing is provided with a discharge 4 terminating in a socket 5 for the upright or standpipe 6.

Across the socket is a bridge or spider 7 having a central boss 8 with a central upwardly facing ball seat 9 therein. The upright 6 has a spider or bridge 10 with a central downwardly facing ball seat 11 therein. The ball 12 is disposed in these seats and supports the standpipe or upright rotatably 60 in the socket and also centers the same therein so that there is a minimum of bearing friction between the socket walls and the standpipe.

The hydraulic packing ring 13 embraces 65 the standpipe and is retained by the collar 14 which is clamped upon the packing ring by means of the bolts 15 engaging the flanges 16 and 17 on the socket and clamping ring respectively. The packing ring is also relieved of wear owing to the centering of the standpipe.

The parts of my improved water column are simple and economical to produce and assemble. The same may be assembled or 75 erected on the ground by persons not skilled as the bearing ball serves both as a centering and supporting means. The structure is easy to operate and durable.

Having thus described my invention, 80 what I claim as new and desire to secure by Letters Patent:

1. In a water column, the combination of a valve casing provided with a standpipe socket having a bridge or spider therein provided with a central upwardly facing ball seat, a standpipe or upright rotatable in said socket and provided with a bridge or spider at its lower end with a downwardly facing central ball seat, a ball disposed in said seats whereby the standpipe is rotatably supported and centered within said socket, a packing ring embracing said standpipe, and a clamping collar for said ring.

2. In a water column, the combination of a conduit member provided with a standpipe socket having a bridge or spider therein provided with a central upwardly facing ball seat, a standpipe or upright rotatable 100

in said socket and provided with a bridge or spider at its lower end with a downwardly facing central ball seat, a ball disposed in said seats whereby the standpipe is rotatably supported and centered within said socket, and a packing ring embracing said stand-pipe.

In witness whereof, I have hereunto set my hand and seal in the presence of two witnesses.

HARRY E. THOMPSON. [L. S.]
